UNITED STATES PATENT OFFICE

ADOLPH KRIER AND JOHN B. KRIER, OF CHICAGO, ILLINOIS, ASSIGNEES TO KRIER
BOILER COMPANY, OF CHICAGO, ILLINOIS, A CORPORATION OF ILLINOIS

BOILER

Application filed April 11, 1931. Serial No. 529,344.

The present invention relates to improvements and betterments, both structural and functional, in boilers and heating appliances, one leading object being to provide a construction or heating apparatus of this character which shall be strong structurally, which shall be simple in design, which can be manufactured at comparatively low cost, which will possess long life, and which will 10 be efficient in operation.

To this end, especially in relation to its efficiency in action, the boiler is constructed to take advantage of the thermo-siphon action of the heated water and the parts of the 15 structure are so arranged and combined as to render the boiler, in large measure, self or automatic cleaning.

To the accomplishment of these and other desirable aims and objects of the invention, 20 we have devised its present, preferred embodiment which is illustrated in the accompanying drawings, forming a part of this specification, and to which reference should be had in connection with the following detailed description.

For simplicity, in the several views of the drawings, like reference characters have been employed to designate the same structural parts.

25 In these drawings:

Figure 1 is a longitudinal, vertical, central section through the improved boiler on line 1—1 of Figure 2;

Figure 2 is a vertical cross-section of the 30 construction on line 2—2 of Figure 1; and

Figure 3 is a similar cross-section on line 3—3 of Figure 1.

As is clearly presented in this drawing, 35 the novel and improved boiler, which is designed and adapted to rest on a brick or metal setting, including brick-walls 11, 11 and metal plates 12, 12 defining and enclosing an ash-pit 13 and supporting a grate 14 of any usual or appropriate construction, includes an outer, metal shell comprising a curved top 15 and vertical side-walls 16, 16, such outer shell having a front, flanged head or wall 17 and a corresponding, flanged back head or wall 18, both of which may be riveted or welded

to the curved plate forming the other portion of the outer shell or casing.

As is presented in Figure 1, these end heads or walls are further secured in position and the structure as a whole stiffened and fortified 55 by stay-rods 19 fastening them to the main sheet of the outer casing.

Inside of such outer shell is an inner shell or casing forming a relatively-long, main combustion-chamber 21, which, at its rear 60 end, connects directly with a back, supplemental or auxiliary combustion-chamber 22, which extends above the crown-sheet of the main-chamber, such upper part of the rear chamber connecting with and communicating 65 with forwardly-extended flues or tubes 23 which reach to the front of the boiler.

Such main or principal combustion space is formed by a single metal sheet bent to provide the upwardly-arched, desirable semi-cylindrical, crown-sheet 24 and depending side-walls 25, 25 which are spaced inwardly 70 away from the companion, outer walls 16, 16 to provide side water-legs 26, 26.

The front end of such inner shell is provided with a flanged head or end-wall 27 located inwardly away from the complementary, outer-shell end-wall 17, thereby supplying 75 a front water-leg 28.

As is shown in Figure 1, the front of the 80 boiler is equipped with a closure 29 for the ash-pit fitted with a suitable door giving ready access to the ash-pit, with a fire-box doorway and its associated door 31 leading to the fire-box, and with a smoke-box 32 with 85 which the front ends of the flues 23 connect and which is adapted for association with the stack or chimney through the exit or discharge opening 33 in its top.

The sheet-metal side-walls 34, 34 of the 90 higher chamber 22 may be integral with the side-walls 25, 25 of the main combustion-chamber, or they may be separate plates with their front edges riveted or welded to the rear edges of the plates 25, 25, the side water-legs between the inner and outer shells extending the full height of such rear chamber 95 22 at those points.

A flanged head or rear end-wall 35 closes 100 the back end of the internal shell and an aper-

tured flue-plate 36 is present between the crown-sheet 24 of the main chamber, the top wall of the auxiliary chamber, and the side-walls of the latter, such flue-plate forming an integral section of one of the plates or constituting a separate element riveted or welded in place.

A hollow, water-filled bridge-wall 37, formed of separated side-plates 38, 38, a flat, bottom plate 39 and a bent, top plate 41 extends from side-wall to side-wall of the combustion-chamber just to the rear of the grate 14 and the ends of its four plates 37, 38, 38, 39 project into properly-shaped apertures in the plates 25, 25 and are welded around their borders.

As is clearly depicted in Figure 2, the top plate 41 of such bridge-wall slopes upwardly in opposite directions from its center, whereby to facilitate the upward flow of heated water therebeneath into the side water-legs of the boiler with which the interior of the wall is directly connected.

In order to strengthen the bridge-wall, if required, it may be provided with a suitable number of stay-bolts 40.

In the fire-box above the grate 14, the boiler is provided with a hollow, water-filled smoke arch or baffle 42 of almost semi-circular form and composed of sheet-metal side-plates 43, 43 with their edges conforming to the curvature of the crown-sheet 24 and a sheet-metal bottom-plate 44, which if preferred, may comprise a flange on one of the side-plates 43 welded along its free edge to the bottom of the companion side-plate.

The crown-sheet 24 is cut out to receive the curved or rounded edges of such side-plates 43, 43 which are welded to the margins of such opening, so that the interior of the smoke-arch is in direct communication with the water-space above the crown-sheet.

In order to prevent a pocket or relatively dead space in front of such smoke-arch or wall from which the gases of combustion could not readily escape, the arch is provided with a pair of tubular passage 45, 45 through it.

At a suitable distance to the rear of the bridge-wall 37, a hollow, water-filled combustion-arch 46 extends downwardly from the crown-sheet to a point below the top of the bridge-wall, such arch being substantially like arch 42 except that it is about twice as deep and, therefore, connects together the two side water-legs of the boiler, as well as being in communication with the water space above the crown-sheet, and this arch has no tubular passages through it corresponding to the parts 45, but owing to its greater size, its side-walls are tied together by stay-bolts 47, 47.

An understanding of this construction will show that it has an extra large fire-box and combustion-chamber which are surrounded at both sides, front, top and rear with wide

water spaces, providing for a great amount of direct and effective heating surface and allowing the combustion gases to expand adequately and to complete their combustion fully before entering the boiler tubes or flues.

The water-cooled smoke-arch, bridge-wall and combustion-chamber arch add very materially to the direct heating surface, such barriers or hollow cross-walls being so located that they are exposed directly to the radiant heat of the blazing fire.

The thermo-siphon action on the water in these hollow cross-members insures continuous and efficient circulation of the water in the boiler and a more even or uniform temperature of the water throughout the boiler, such water circulation drawing the water from the cooler water-legs and carrying it effectively into the more highly heated portions of the boiler.

These water-filled cross-members also mechanically tie together the side-walls of the boiler, assisting in preventing their distortion or bulging, and the front and rear ones are spaced in such a manner as to effectively stiffen and strengthen the crown-sheet, hence eliminating the necessity for radial stays for such sheet, the employment of which would preclude the most desirable arrangement and disposition of the tubes or flues.

Due to the fact that the crown-sheet is arched upwardly, it promotes efficient combustion and it is self-cleaning in that it prevents scale and sediment accumulation on its surface and thus maintains its ready and able heat transfer to the water.

The bottoms of the several water-legs may be closed in any appropriate manner by the use of a flange on one of the two plates which is welded to the opposite plate.

The plate sections or portions 24, 25, 25, 34, 34 of the inner shell are fastened to the side-walls of the outer shell by horizontal stay-bolts 48, 48 of different lengths, and the top wall of the back combustion-chamber 22 is secured to the top of the outer shell by vertically-disposed stay-bolts 49.

Horizontal stay-bolts 51 extend between some of the flues 23 and secure together the side-walls of the outer shell above the crown-sheet, all as is clearly illustrated.

It will be clear from the illustration of the boiler that the smoke-arch extends downwardly below the top of the bridge-wall and that the combustion-chamber arch projects downwardly a substantial distance below the top of a bridge-wall, such three members forming a tortuous passage for the gases which will cause them to co-mingle to secure their more complete combustion and will result in their intimate contact with the various heating surfaces of the boiler, whereby to give the latter a satisfactory economy of operation.

The invention as presented in the append-

ed claims is not limited and restricted to the precise and exact details of structure shown and described, but is susceptible of a variety of embodiments varying more or less in structural aspects but all incorporating the fundamental principles of the invention.

Stated somewhat differently, more or less major or minor modifications may be made in the boiler set forth, without departure from the heart of the invention and without the loss or sacrifice of any of its material benefits and advantages.

We claim:

1. In a boiler, the combination of an outer sheet-metal shell, an inner sheet-metal shell forming a main combustion-chamber and a supplemental combustion-chamber to the rear of, communicating with, and extending higher than said main-chamber, said inner shell being spaced away from said outer shell at all points to provide side, front and rear water-legs and being curved upwardly at the top of said main-chamber to provide a crown-sheet therefor, flues above said crown-sheet and connected at their rear ends to the upper portion of said supplemental combustion-chamber, a hollow bridge-wall to the rear of said grate having the ends of its interior directly connected to the interior of the opposite side water-legs, the top of said bridge-wall sloping upwardly and outwardly in opposite directions from its center, a hollow smoke-arch depending from said crown-sheet above said grate sufficiently to overlap at least a portion of said bridge-wall and having its top and ends opening through said crown-sheet to the water space above, and a hollow combustion-chamber arch depending from said crown-sheet to the rear of said bridge-wall and extending down below the top of said bridge-wall, said combustion-chamber arch opening at its top and ends through said crown-sheet and through said inner-shell side-walls into said side water-legs.

2. In a boiler, the combination of an outer sheet-metal shell, an inner sheet-metal shell forming a main combustion-chamber and a supplemental combustion-chamber to the rear of, communicating with, and extending higher than said main-chamber, said inner shell being spaced away from said outer shell at all points to provide side, front and rear water-legs and being curved upwardly at the top of said main-chamber to provide a crown-sheet therefor, flues above said crown-sheet and connected at their rear ends to the upper portion of said supplemental combustion-chamber, a grate in the front part of said main combustion-chamber, a hollow bridge-wall to the rear of said grate having the ends of its interior directly connected to the interior of the opposite side water-legs, a hollow smoke-arch depending from said crown-sheet above said grate and having its top and ends opening through said crown-sheet, and a hollow combustion-chamber arch depending from said crown-sheet to the rear of said bridge-wall and opening at its top and ends through said crown-sheet and through said inner-shell side-walls into said side water-legs.

ficiently to overlap at least a portion of said bridge-wall and having its top and ends opening through said crown-sheet, and a hollow combustion-chamber arch depending from said crown-sheet to the rear of said bridge-wall and extending down below the top of said bridge-wall, said combustion-chamber arch opening at its top and ends through said crown-sheet and through said inner-shell side-walls into said side water-legs.

3. In a boiler, the combination of an outer sheet-metal shell, an inner sheet-metal shell forming a main combustion-chamber and a supplemental combustion-chamber to the rear of, communicating with, and extending higher than said main-chamber, said inner shell being spaced away from said outer shell at all points to provide side, front and rear water-legs and being curved upwardly at the top of said main-chamber to provide a crown-sheet therefor, flues above said crown-sheet and connected at their rear ends to the upper portion of said supplemental combustion-chamber, a grate in the front part of said main combustion-chamber, a hollow bridge-wall to the rear of said grate having the ends of its interior directly connected to the interior of the opposite side water-legs, a hollow smoke-arch depending from said crown-sheet above said grate and having its top and ends opening through said crown-sheet, and a hollow combustion-chamber arch depending from said crown-sheet to the rear of said bridge-wall and opening at its top and ends through said crown-sheet and through said inner-shell side-walls into said side water-legs.

In witness whereof we have hereunto set our hands.

ADOLPH KRIER.
JOHN B. KRIER.
